UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 12,147, dated February 1, 1881.

Application filed December 28, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

- 10 o The design comprises the following architectural elements, viz: an arched bridge, A, over a sheet of water, a flight of steps, B, terminating in an archway, C, and having a balustrade, D, towers E F, and the architectural 15 ornament G.

The design also comprises a group of flowers and foliage, H, rising from an urn or vase, I, and floral and foliage designs, more or less intricate, partially covering the architectural elements above named.
